UNITED STATES PATENT OFFICE.

EUGENE F. COOK, OF ST. LOUIS, MISSOURI.

DESIGN FOR A PACKING-RING.

53,001.

Specification for Design.

Patented Feb. 18, 1919.

Application filed January 27, 1917. Serial No. 145,010. Term of patent 14 years.

To all whom it may concern:

Be it known that I, EUGENE F. COOK, a citizen of the United States, residing at St. Louis, in the State of Missouri, have invented a new, original, and ornamental Design for Packing-Rings, of which the following is a specification, reference being had to the accompanying drawing, forming part hereof.

The figure is a perspective of a packing ring.

I claim:

The ornamental design for a packing ring, substantially as shown.

In testimony whereof, I have signed my name to this specification this 24th day of January, 1917.

EUGENE F. COOK.
